UNITED STATES PATENT OFFICE.

JAMES A. MOULD, OF MILWAUKEE, WISCONSIN, ASSIGNOR TO EVINRUDE MOTOR COMPANY, OF MILWAUKEE, WISCONSIN.

OUTBOARD MOTOR.

Application filed March 5, 1923. Serial No. 622,739.

To all whom it may concern:

Be it known that I, JAMES A. MOULD, a citizen of the United States, residing at Milwaukee, county of Milwaukee, and State of Wisconsin, have invented new and useful Improvements in Outboard Motors, of which the following is a specification.

This invention relates to improvements in outboard motors. More particularly this invention relates to a novel assembly of the water circulating means with respect to the steering and power transmitting connections and a novel submersible housing construction facilitating the assembly and disposal 15 of the parts of the motor.

It is the particular object of this invention to provide an outboard motor wherein the disposal and drive of the water pump and the arrangement of the supply duct 20 leading from the pump to the cooling passages of the engine will be more compactly and conveniently arranged with reference to the remaining parts of the motor than has heretofore been the case.

Further objects of this invention are to provide a novel construction for the submerged gear housing of an outboard motor which is adapted to expedite and facilitate the assembly of the device; to provide driving connections for the water pump such that the pump can be driven positively and conveniently from the main driving shaft of the device without necessitating the transmission of power to the pump through the 30 submerged gearing which drives the propeller; and to provide a construction wherein the supply pipes leading from the pump to the water jackets of the engine will be connected in a manner to afford constant 35 communication between the pump and the engine during steering and during the reverse operation, although the position of the pump is affected both by the steering and the reverse of the motor.

In the drawings:

Fig. 1 is a side elevation of the upper portions of a so-called outboard motor embodying this invention.

Fig. 2 is a vertical, central section on an enlarged scale through the lower portions of an outboard motor embodying this invention.

Like parts are identified by the same ref-

erence characters throughout the several views.

The outboard motor shown in the accompanying drawings is of the general type illustrated in the patent to Evinrude No. 1,001,260, August 22, 1911, and the patent to Heck and Vitek No. 1,161,935, November 30, 1915.

The bracket 5 has a portion 6 adapted to extend downwardly outside of the transom of a boat and a portion 7 provided with a screw threaded aperture in which the screw 8 may be adjusted to engage the transom with a clamping action. The bracket 5 extends upwardly above the transom and is provided with a transverse axis pin 10 upon which the entire engine and propulsion device is hingedly mounted.

The engine E includes a crank case 11, a cylinder 12 to which fuel is supplied from a tank 13, a fly wheel 14 and a crank shaft 15 disposed vertically and adapted to receive power developed in the cylinder 12. The crank shaft will, of course, be provided with a crank to which a piston and connecting rod reciprocable in the cylinder 12 will be attached in the manner shown in the patents aforesaid.

The crank shaft 15 is extended downwardly through an independently rotatable housing 16 to a bevel gear 17 which meshes with a bevel gear 18 upon the propeller shaft 19. The propeller shaft and gearing are disposed in a submerged gear housing, which will be designated in its entirety by the reference character 20 and will herein-after be more particularly described. The propeller shaft 19 extends outwardly at the rear of said housing and carries a propeller 21. At this time it is desirable to bring out only the fact that the submerged gear housing 20 is supported by the rotatable shaft 95 housing 16 and a boat to which this device is attached may be steered or reversed by the proper manipulation of the tubular housing 16, whereby the thrust of the propeller is directed as desired.

Immediately beneath the crank case 11 is a casing 23 into which a tiller 24 extends. The casing 23 houses a latch mechanism which may take the form of that disclosed in the patent to Heck and Vitek aforesaid, or may constitute the improved device dis-

closed in a companion application copending herewith. The latch mechanism within the casing will be such that for ordinary steering purposes the tubular housing 16 will be locked to the tiller 24 to oscillate therewith. For reversing purposes the latch mechanism can be released by partial rotation of the tiller handle as disclosed more particularly in the patent to C. J. Meyer, No. 1,191,10 211, July 18, 1916. The latching mechanism within casing 23 will thereupon release the tubular housing 16 for a rotation of 180° independent of the tiller, whereupon the thrust of the propeller will be reversed and 15 the tubular housing 16 will automatically be connected to the tiller for steering purposes as before.

In the precise means by which steering is effected the device herein disclosed and embodying the present invention differs from those devices disclosed in the patents above referred to. As is clearly shown in Fig. 1 the tiller 24 is connected directly with the casing 23 so that the tiller cannot be oscillated from 25 side to side without also oscillating casing 23. This casing is in supporting relation to the crank case 11 and cylinder 12 and the rest of the internal combustion engine which motivates the device. Accordingly, steering 30 is seen to be accomplished by oscillating the entire engine and in fact the entire device with the exception of bracket 5 upon the axis of the tubular housing 16.

This steering movement is made possible 35 by the provision beneath casing 23 of a sleeve-like, downward extension 26. A two-part bearing sleeve 27 clamps around the sleeve-like extension 26 of casing 23 and is provided with a flange 28 in supporting 40 relation to the casing. The two-part bearing sleeve 27 is provided integrally with a pair of forwardly extending ears, one of which is shown in section at 29 and which are apertured to receive the transverse axis 45 pin 10 carried by bracket 5. Thus the bearing sleeve 27 is hingedly supported directly from bracket 5 and all of the remaining parts of the outboard motor are rotatably supported from the bearing sleeve.

50 The tubular housing 16 extends upwardly within sleeve 26 as best shown in Fig. 2 and through the latch mechanism where it is releasably engaged with a tiller as disclosed in the patents referred to above or 55 as disclosed more particularly in a companion application co-pending herewith. Thus, whereas the sleeve 26 always moves in accordance with tiller movements the tubular shaft 16 will, upon the occasion of reversals, 60 rotate through 180° independently of sleeve 26 and of the tiller.

After the general explanation given above with regard to the relative movements which take place between the several parts of an 65 outboard motor of this type, the following

discussion of the specific structure of the lower parts of such a motor will be more readily understood.

The submerged gear housing which is designated in its entirety by the reference character 20 is preferably made up of two parts 31 and 32 which are joined in a horizontal plane including the axis of propeller shaft 19. Suitable bolts and nuts, such as are shown at 33, may be utilized to secure 75 the two parts of the submerged gear housing together. The assembled housing provides a recess at 34 in which the outer race of a radial and thrust anti-friction bearing for the propeller shaft 19 is provided. The 80 bearing is designated in its entirety by the reference character 35. An end plate 36 for the housing 20 carries integrally a bearing sleeve 37 which supports the rear end of propeller shaft 19 and also serves as a seat for 85 the thrust bearing 38. This last mentioned bearing absorbs the thrust of bevel gear 18 through which the propeller shaft 19 is driven as heretofore explained. A bushing 39 is preferably interposed between the bearing sleeve 37 and shaft 19.

The upper half 31 of the submerged gear housing 20 is preferably formed integrally with an upwardly extending sleeve portion 40 from which the pump cylinder 41 extends rearwardly and to which the webs or vanes 42, 43 and 44 are integrally attached. Sleeve 40 is recessed at 45 to receive a bearing 46 for the drive shaft 15. The tubular housing 16 for the drive shaft extends downwardly into sleeve 40 and is secured therein as by set screw which are shown in dotted lines at 47. In this way the whole of the submerged gear housing 20, together with the pump cylinder 41 and the webs or veins 42, 43 and 44 is supported from the dirigible tubular shaft housing 16 and is rotatable therewith upon the axis of said housing. It will be noted that when the tubular housing 16 is rotated on its axis the direction of thrust of the propeller 21 is not only changed, but also the vanes 42, 43, and 44 mounted upon the upper half 31 of the gear housing 20 act as a rudder. The skeg or fin 45 assists in this function and furthermore protects the propeller 21 from injury by obstacles encountered in the water.

The pump in this device includes a head portion 50 in which inlet and outlet check valves 51 and 52, respectively, are provided. 120 A cylinder sleeve 53 may be integral with the pump head 50 and comprises a lining for cylinder 41 in which it may be secured by a set screw indicated in dotted lines at 54. The piston of the pump is preferably 125 of the displacement type and comprises simply a tubular member 55 closed at 56 and open at the opposite end to receive a spring 57 which seats against an inner wall 130 of the head portion 50. The spring normal-

ly forces the closed head 56 of cylinder 55 into contact with a cam 60 carried directly on the driving shaft 15 and disposed within the sleeve 40 which is integral with the upper portion 31 of the submerged gear housing.

The outlet port of the valve communicates with a pipe 61 which preferably follows close to the rear margin of the rudder blade or web 43 and is extended by means of a fitting 62 through the wall of the dirigible, tubular shaft housing 16.

Immediately above this point the tubular shaft housing 16 extends between the rearwardly projecting arms 64 of bracket 5 and to obviate the necessity for using a flexible water conductor and also to make impossible injury to the water tube when the tube and the shaft housing 16 are rotated with respect to said arms the tube is led upwardly on the inside of shaft housing 16 where it is protected from contact with arms 64 during its rotation with respect thereto.

That portion of the water conductor which extends upwardly from fitting 62 within the shaft housing 16 is designated by reference character 65. It terminates in communication with a recess 66 in an annulus 67 which fits closely within the shaft housing 16. An aperture 68 in the shaft housing provides for the egress of water from the recess 66 to the exterior of said housing.

The sleeve 26 which has heretofore been described as being connected with latch casting 23 is enlarged at 69 and is shouldered at 70 to provide a seat for packing ring 71. Immediately beneath the packing ring is an annulus 72 having an I-shaped cross section, the inner and outer recesses of which are connected by one or more openings 73. The inner recess of the annulus 72 receives water emerging through opening 68 in the shaft housing 16 and the outer recess of said annulus communicates with the interior of the fitting 74 from which pipe 75 leads upwardly to the water jackets of the engine cylinders.

The arrangement is such that with the parts in the position in which they appear in the accompanying drawings through communication is established between the pump and the cooling jackets of the engine cylinder through pipe 61, fitting 62, internal pipe 65, recess 66 of the annulus 67, opening 68 in shaft housing 16, opening 73 in the outer annulus 72, fitting 74 and pipe 75. Inasmuch as the entire engine is rotated within bearing sleeve 27 for steering purposes, it will be obvious that no flexible tubing is necessary to convey water from the pump to the engine. Furthermore, the opening 68 in the shaft housing 16 and the opening shown at 73 in the outer annulus 72 will normally be in registry to permit a direct flow

of water from the internal pipe 65 to the outer pipe 75. When, however, the motor is reversed the shaft housing 16 and all parts connected with said housing will be caused to rotate for 180° and during the time of such reversal the water will be caused to flow 180° around the outside of shaft housing 16 in one of the channels of annulus 72. The escape of water beneath said annulus is prevented by a packing ring 77 which is tightened by a packing nut 78.

If it is necessary to prevent leakage along the tubular shaft housing 16 a small peripheral recess 79 may be formed in the enlarged portion 69 of sleeve 26. This recess may be drained by a duct 80 leading to the exterior of the device.

The construction described has many advantages. In the first place the assembly of the entire propulsion device or outboard motor is facilitated. The two part construction of the submerged gear housing 20 makes it possible to inspect the gearing and shafting during assembly to ascertain whether or not the parts are in proper alignment. The drive shaft 15 with the cam 60, the assembled ball bearing 46 and the bevel gear 17 all-ready positioned thereon is simply thrust into the lower end of housing member 31 and up through the shaft 95 housing 16 until the outer race of ball bearing 46 is properly positioned in the recess 45. Thereupon the propeller shaft 19 with all of its bearings and with its bevel gear 18 in assembled relation upon it is set in place 100 within the upper housing member 31 and the lower housing member 32 is clamped to the upper housing member to seal the device. Thereafter the pump mechanism can be inserted into the cylinder member 41 bodily 105 and secured in place by set screw 54. It will be noted that the pump is actually built into the rudder and that the whole structure is not only easily assembled but is compact and has great strength.

In many outboard motors which have previously been constructed the pump has been driven from a cam on the propeller shaft. In the present device the cam which drives the pump is mounted directly upon the driving shaft 15 and thus the bevel gears 17 and 18 are relieved of the pulsating and variable load to which they have heretofore been subjected by pump action.

Another advantage in the construction 120 illustrated lies in the fact that no flexible tubing is necessary to transmit water from the pump to the cooling jackets of the engine. The mechanism by which the flexible conductor for water has been done away 125 with, comprises, first a construction wherein the entire engine moves with the pump-carrying housing for ordinary steering purposes and, secondly, the channeled annuli providing for a continuous flow of water be- 130

tween relatively rotatable parts, whereby the flow is not interrupted at such times as the motor is reversed and the pump and attached mechanism are caused to rotate with respect 5 to the engine.

I claim:-

1. An outboard motor including an upright drive shaft, a substantially horizontal propeller shaft, gearing connecting the drive shaft with the propeller shaft, a housing for said gearing and said propeller shaft provided with bearings for the propeller shaft, and a sleeve extending upwardly about said drive shaft from said housing and provided 10 with a laterally extending arm in communication with the interior of said sleeve, said arm comprising a support for a pump.

2. An outboard motor including an upright drive shaft, a substantially horizontal propeller shaft, gearing connecting said drive shaft with said propeller shaft, a housing for said gearing, a sleeve extending upwardly from said housing about said drive shaft, a laterally projecting sleeve in communication with the interior of said first mentioned sleeve, and pump mechanism including a piston operable within said laterally projecting sleeve and arranged for actuation from said drive shaft.

3. In an outboard motor the combination with a drive shaft, of a sleeve surrounding said shaft and extending in the direction thereof, a subordinate sleeve projecting laterally from a submersible portion of the first mentioned sleeve, pump mechanism including a piston reciprocable in said subordinate sleeve, and motion transmitting connections for imparting a reciprocating movement to said pump mechanism from said drive shaft.

4. In an outboard motor the combination with a drive shaft, of a sleeve surrounding said shaft and extending in the direction thereof, a subordinate sleeve projecting laterally from a submersible portion of the first mentioned sleeve, pump mechanism including a piston reciprocable in said subordinate sleeve, and a cam upon said drive shaft adapted to act directly upon said piston.

5. In an outboard motor the combination with a drive shaft, of a dirigible housing enclosing said shaft, a sleeve projecting laterally from said housing and in communication therewith, a pump head provided with valved inlet and outlet ports and with a lining receivable into said sleeve, a pump plunger reciprocable within said lining and provided with a spring normally urging it in the direction of said drive shaft, and a cam on the drive shaft in registry with said plunger and adapted to impart reciprocatory motion thereto.

6. In an outboard motor the combination with an angularly related drive shaft and propeller shaft provided with motion trans-

mitting connections for actuating the latter from the former, of an eccentric device mounted upon the drive shaft for rotation therewith, and a housing enclosing a portion of each of said shafts together with said motion transmitting connections and said eccentric device, a pump cylinder supported from said housing and extending laterally with respect to the drive shaft in registry with the eccentric device thereon, and a set 70 of webs integrally connecting said cylinder with portions of said housing above and below it.

7. In an outboard motor a housing element comprising a two-part submersible casing, the parts thereof being separable substantially in a horizontal plane and provided with mutually registering recesses adapted to receive bearings for a shaft, an integral, tubular element extending outwardly from 80 one of the parts of said casing, and a pump cylinder integral with said element and projecting laterally therefrom in a plane including the axis of said casing.

8. In an outboard motor a housing element comprising a two-part submersible casing, the parts thereof being separable substantially in a horizontal plane and provided with mutually registering recesses 85 adapted to receive bearings for a shaft, an integral, tubular element extending outwardly from one of the parts of said casing, a pump cylinder integral with said element and projecting laterally therefrom in a plane including the axis of said casing, and a web 90 integrally connecting said cylinder with said tubular element above the cylinder and with said element and with a part of said casing below the cylinder.

9. In an outboard motor a submersible 105 housing including a casing having two parts separably joined together on a plane including the major axis of said casing, a fin extending downwardly beneath a first part of said casing, a drive shaft housing extending oppositely from a second part of said casing substantially at right angles to the axis thereof and in communication with the interior of the casing, and a set of webs 110 integrally connecting each side of said drive shaft housing with said second part of said casing and lying together with said fin in a common plane, one of said webs being formed to provide a pump cylinder in communication with the interior of said shaft 115 housing and extending in the plane of said web.

10. In an outboard motor a submersible housing including a casing having two parts separably joined together upon a substantially horizontal plane including the major axis of said casing, a drive shaft housing integral with one of the parts of said casing 125 and extending upwardly therefrom, a fin extending downwardly from the other part of 130

14. An outboard motor including an upright drive shaft, a housing for said shaft mounted for oscillation and rotation co-axially with said shaft, a propeller arranged for actuation from said drive shaft and supported from said housing, whereby the oscillation and rotation of said housing will, respectively, steer and reverse the thrust of said propeller, pump mechanism arranged for actuation from said drive shaft and supported from said housing for oscillation and rotation therewith, an outlet pipe for said pump and a second pipe arranged for oscillation with said drive shaft but not for rotation therewith, said first and second pipes being in communication irrespective of the rotation of said housing. 70
15. An outboard motor including a jacketed cylinder mounted for oscillation upon a substantially vertical axis, a drive shaft extending downwardly therefrom co-axially with the axis of oscillation of said cylinder, a housing for said drive shaft, a propeller arranged to be driven from said drive shaft and supported from said housing, whereby said motor may be steered or reversed by a suitable actuation of said housing, a pump supported from said housing and provided with a piston arranged for reciprocation from said drive shaft, a bracket in supporting relation to said cylinder and provided with rearwardly projecting arms embracing said housing, and a supply pipe from said pump leading upwardly within said housing and between the wall thereof and the drive shaft therein. 75
16. An outboard motor including a bracket, of a bearing sleeve supported therefrom, an internal combustion engine mounted for oscillation co-axially with said sleeve and provided with a drive shaft extending therethrough, an internal sleeve connected with said engine and extending through said bearing sleeve, a tubular shaft 80 housing within said internal sleeve and enclosing said shaft, a pump supported from said shaft housing, an annulus connected with said housing and provided with a peripheral recess in communication with said pump, an annulus connected with said internal sleeve and provided with an annular recess in registry with the peripheral recess of the first mentioned annulus, said recesses being in communication, and a pipe 85 extending from the recess of the second annulus to the engine, whereby said pump and engine are in constant communication irrespective of the relative rotative position of said inner sleeve and shaft housing. 90
17. An outboard motor including an internal combustion engine provided with an upright drive shaft, a dirigible housing enclosing said shaft and rotatably adjustable independently of said engine, a sleeve connected with said engine and encircling the housing, a pump supported from the housing, a pipe leading upwardly from the pump within the housing, an annulus within the housing provided with a recess in communication with said pipe, an annulus exterior to the housing provided with an annular recess in communication with the recess of the inner annulus through an aperture of the housing, and a pipe connected with said engine and in communication with the annular recess of the outer annulus. 95
18. An outboard motor including an internal combustion engine provided with an upright drive shaft, a dirigible housing surrounding said drive shaft and rotatably adjustable independently of said engine, a sleeve connected with said engine and surrounding a portion of said housing, the lower end of said sleeve being spaced per- 100
19. An outboard motor including a jacketed cylinder, an upright drive shaft, said cylinder being mounted for oscillation co-axially with said shaft, a tubular housing for said shaft supported for oscillation co-axially therewith and in unison with said cylinder for steering purposes and rotatable independently of said cylinder for reversing purposes, a propeller supported from said housing and arranged for actuation from said drive shaft, whereby said motor may be steered and reversed by the oscillation and rotation of said housing, a pump supported from said housing, a pipe leading upwardly from said pump and connected with said housing for movement therewith and with said pump, a pipe leading downwardly from the jacket of said cylinder and connected therewith for oscillation with said cylinder, and means for establishing permanent communication between said pipes irrespective of their relative positions. 105
20. An outboard motor including an upright drive shaft, a housing for said shaft mounted for oscillation and rotation co-axially with said shaft, a propeller arranged for actuation from said drive shaft and supported from said housing, whereby the oscillation and rotation of said housing will, respectively, steer and reverse the thrust of said propeller, pump mechanism arranged for actuation from said drive shaft and supported from said housing for oscillation and rotation therewith, an outlet pipe for said pump and a second pipe arranged for oscillation with said drive shaft but not for rotation therewith, said first and second pipes being in communication irrespective of the rotation of said housing. 110
21. An outboard motor including a bracket, of a bearing sleeve supported therefrom, an internal combustion engine mounted for oscillation co-axially with said sleeve and provided with a drive shaft extending therethrough, an internal sleeve connected with said engine and extending through said bearing sleeve, a tubular shaft 115 housing within said internal sleeve and enclosing said shaft, a pump supported from said shaft housing, an annulus connected with said housing and provided with a peripheral recess in communication with said pump, an annulus connected with said internal sleeve and provided with an annular recess in registry with the peripheral recess of the first mentioned annulus, said recesses being in communication, and a pipe extending from the recess of the second annulus to the engine, whereby said pump and engine are in constant communication irrespective of the relative rotative position of said inner sleeve and shaft housing. 120
22. An outboard motor including an internal combustion engine provided with an upright drive shaft, a dirigible housing enclosing said shaft and rotatably adjustable independently of said engine, a sleeve connected with said engine and encircling the housing, a pump supported from the housing, a pipe leading upwardly from the pump within the housing, an annulus within the housing provided with a recess in communication with said pipe, an annulus exterior to the housing provided with an annular recess in communication with the recess of the inner annulus through an aperture of the housing, and a pipe connected with said engine and in communication with the annular recess of the outer annulus. 125
23. An outboard motor including an internal combustion engine provided with an upright drive shaft, a dirigible housing surrounding said drive shaft and rotatably adjustable independently of said engine, a sleeve connected with said engine and surrounding a portion of said housing, the lower end of said sleeve being spaced per- 130

6
ipherally from said housing and internally threaded, a pipe leading upwardly within the housing and adapted to deliver fluid through an aperture in the wall thereof, an annulus disposed within the space between said sleeve and said housing provided with an annular recess and in communication

through an aperture in said housing with said pipe, a second pipe connected with said sleeve and in communication with the recess of said annulus, and a ring nut in threaded engagement with said sleeve below said annulus and encircling said housing.
